(57) CLAIM

I claim the ornamental design for a light fixture, as shown and described.

DESCRIPTION

FIG. 1 is a top perspective view of the light fixture, showing my new design;

FIG. 2 is a top view thereof;

FIG. 3 is a bottom view thereof;

FIG. 4 is a right view thereof;

FIG. 5 is a left view thereof;

FIG. 6 is a front view thereof; and,

FIG. 7 is a rear view thereof.

The broken line showing in the drawings is included for the purpose of illustrating unclaimed portions of the light fixture and forms no part of the claimed design.

1 Claim, 4 Drawing Sheets
